CLAIM

The ornamental design for a electric window operator, as shown and described.

DESCRIPTION

FIG. 1 is a perspective view for an electric window operator assembled,

FIG. 2 is a another perspective view thereof,

FIG. 3 is a front elevational view thereof,

FIG. 4 is right side elevational view thereof,

FIG. 5 is a left side elevational view thereof,

FIG. 6 is a top plan view thereof,

FIG. 7 is a bottom plan view thereof,

FIG. 8 is a perspective view for an electric window operator assembled,

FIG. 9 is a another perspective view thereof,

FIG. 10 is a front elevational view thereof,

FIG. 11 is right side elevational view thereof,

FIG. 12 is a left side elevational view thereof,

FIG. 13 is a top plan view thereof,

FIG. 14 is a bottom plan view thereof,

FIG. 15 is a perspective view for an electric window operator assembled,

FIG. 16 is a another perspective view thereof,

FIG. 17 is a front elevational view thereof,

FIG. 18 is right side elevational view thereof,

FIG. 19 is a left side elevational view thereof,

FIG. 20 is a top plan view thereof; and,

FIG. 21 is a bottom plan view thereof.

The broken lines in the drawings illustrate portions of an electrical window operator which form no part of the claimed design.
